UNITED STATES PATENT OFFICE.

LOUIS STEINBERGER, OF BROOKLYN, NEW YORK.

INSULATOR.

1,426,516.

Specification of Letters Patent. Patented Aug. 22, 1922.

Application filed April 29, 1918. Serial No. 231,336.

To all whom it may concern:

Be it known that I, LOUIS STEINBERGER, a citizen of the United States, and a resident of the borough of Brooklyn, county of 5 Kings, city and State of New York, have invented certain new and useful Improvements in Insulators, of which the following is a specification.

My invention relates to an insulator construction having particular reference to the 10 type and formation of the strain members embedded within the insulator body.

One of the objects of my invention is to provide an insulator with strain members 15 of such construction as to lessen the lines of stress and strain within the body of the insulator and thereby to lessen the concentration of heat in the central portion of the insulator body in which the strain members 20 are embedded.

Another object of my invention is to so construct the strain members of an insulator 25 that the bridge portions or members thereof will act as electrostatic stress distributors and will co-operate with arms projecting 30 from the legs of the strain members to distribute the stresses and strains within the center of the body of the insulator and thus eliminate concentration of the electrical energy at any point.

Other objects will appear from the subjoined specification and claims.

Referring to the drawings, Fig. 1 is a view 35 partly in section and partly in side elevation of an insulator embodying my invention.

Fig. 2 is a plan in detail of an assembly 40 of strain members embodying my invention in the positions in which they are placed in the body of the insulator when molded therein.

Fig. 3 is a perspective side view of an 45 assemblage of strain members embodying my invention showing their position in the body of the insulator.

Fig. 4 is a plan view of an assembly 50 of strain members showing a modified form of my invention.

Fig. 5 is a view partly in side elevation 55 and partly in section illustrating the strain members as shown in Fig. 4.

The insulating material forming the body of my insulator may be of any suitable kind, but I prefer to use the insulating material known in the art as "electrose" and the remaining parts are formed of any suitable 60 metal or alloys thereof.

Referring to the drawings, 10 is a body of insulating material which may be of any preferred shape but I have chosen to illustrate a body having a contour as shown in 60 Fig. 1 wherein the side of the insulating body has projecting radially therefrom a central flange 11 of greater diameter than the two radially projecting flanges 12 and 13 at either end. 65

14 is an integral strain member, a portion of which is embedded in the insulator body and 15 is the embedded portion of a two part strain member having legs 16 and 17 projecting from the side of the body of 70 the insulator. 18 is the complementary portion of the two part strain member which is secured to the projecting ends 16 and 17 of the embedded portions by means of nuts 19 and 20 engaging screw threads 21 and 21' and 22 and 22' on the respective ends 75 of the portions 15 and 18 of the strain member, as well known in this art.

The strain members are provided with bridge portions or members 30 and 31 which 80 consist of rings 32 and 33, each of which is substantially circular in cross section and integrally secured to the embedded leg portions or members 34 and 35, 36 and 37 of the respective strain members by means of 85 offset arms 38, 39, 40 and 41 as shown. The strain members are interlocked one with the other so that in case the insulating material should be destroyed the line will not fall to the ground, and they are so situated 90 with respect to each other that the respective rings of the bridge portions of the strain members will be oppositely disposed to each other in the central portion of the body of insulating material. 95

The ring portions of the strain members act as electrostatic stress distributors, and at the same time act as uniform mechanical strain distributors. Because of the open or skeleton construction due to the oppositely 100 disposed ring portions, the formation of heat in the central portion of the insulating body is prevented. As will be seen from the drawings, the legs of the strain members are disposed near to the outer side 105 surface of the body of the insulator so that the generated heat may be carried off quickly from the inner portion of the body of the insulator to prevent the deleterious effects due to the formation of the heat and 110 the retention thereof in the central portion of the insulator.

The amount of offset or length of offset between the leg portions and the ring portions of the strain member is determined by the voltages to be used or applied to the insulator. As will be readily understood, the greater the space between the ring and leg member of the strain member the greater will be the insulation value of the insulator.

Projecting from each of the legs of the strain members which are embedded in the body of the insulating material are metallic arms 50, 51, 52, 53, 54, 55, 56, 57, which are curved so as to lie in lines which are concentric respectively with the ring portion of the strain members. These arms are also so situated on the legs of the strain members that when the strain members are assembled for molding in the insulator body each pair is respectively placed directly opposite the ring portion of the other strain member and in the same horizontal plane therewith. The distances between each arm and adjacent ring portion indicated by the line y in Fig. 2 must be less than the distances indicated by the lines x in Fig. 2 so there will be more insulation between the points a and b than between the points c and d , and thereby the electrical strains and stresses will be distributed between the arms 50 and 51 and the ring portion of the strain member opposite thereto, and the voltage will not cause rupture of the insulating body which would otherwise be the case should the distance x be less than the distance y . The same description applies to the relations and distances between the other arms of the assembled strain members, and therefore it is not necessary to repeat the description, as the description for one serves as a description for all.

In Figs. 4 and 5 I have shown another construction by means of which the electrical stresses and strains are also distributed. In this construction I provide integral projecting fingers 60, 61, 62 and 63, projecting respectively from the ring portions 33' and 32' of the strain members at points diametrically opposite to each other, one pair of fingers projecting upwardly and the other pair of fingers projecting downwardly and in parallelism with the legs of the adjacent strain members. It is therefore seen from this construction that the electrical stresses and strains will be distributed between the fingers or arms (which project from the ring portions of the strain members) and the legs of the adjacent strain members.

The projecting arms or fingers shown in each of the Figures of the drawings serve to distribute the electrical strains and stresses in the center of the insulating body with a result that the danger of rupture due to the concentration of heat is very much lessened.

The relative position and the relation of the respective parts of the several types are

similar to each other and the parts should be adjusted so that the projecting fingers 60, 61 and 62 and 63 are parallel to the supporting legs of the strain members.

As changes of construction could be made within the scope of my invention, it is intended that all matter contained in the above description or shown in the accompanying drawings shall be interpreted as illustrative and not in a limiting sense.

Having now described my invention what I claim as new and desire to secure by Letters Patent is:

1. In a device of the kind described, an insulating body, interlocked strain members embedded therein, said strain members embodying stress distributing rings oppositely disposed to each other, and additional stress distributing members extending from one strain member in the same plane as the stress distributing ring of the other strain member to co-operate therewith.

2. In a device of the kind described, an insulating body, interlocked strain members embedded therein, each strain member consisting of leg portions and a bridge portion said bridge portions being oppositely disposed to each other, stress distributing fingers or arms projecting from the one portion of one strain member and extending in lines parallel to the lines of the other portion of the other strain member.

3. In a device of the kind described, an insulating member, strain members embedded therein, said strain members each having leg portions and a bridge element therebetween embodying a ring shaped portion, the leg portions being offset from said ring shaped portion, each of the leg portions being provided with oppositely projecting arms in substantially the same horizontal plane with the ring portion of the adjacent strain member and extending in a curved line concentric with the ring portion, the distance between the extending arms and the ring portion being less than the distance between the ends of the extending arms and leg portions of the adjacent strain member.

4. In a device of the kind described, a body of insulating material, interlocked strain members embedded therein, each strain member consisting of leg portions extending outside of the body of insulating material and a ring shaped bridge portion connected to the said leg portions and wholly embedded within the center of the insulating body, projections from the leg portions of one strain member extending in lines parallel to the rings of the bridge portions of the other strain member.

5. In a device of the kind described, a body of insulating material, interlocked strain members embedded therein, each strain member consisting of leg portions extending outside the body of insulating material and

a ring shaped bridge portion connected to the said leg portions and wholly embedded within the center of the insulating body, said ring shaped bridge portions situated 5 opposite to each other, projections from the leg portions of one strain member extending in lines parallel to the line of the ring shaped bridge portion of the other strain member, the lines of the respective projections and rings lying in the same plane with 10 each other.

6. In a device of the kind described, an insulating body, interlocked strain members embedded therein, each strain member consisting of leg portions extending outside the insulating body, and a ring shaped bridge portion connected to the said leg portions wholly embedded within the center of the insulating body, projections from the respective 15 leg portions extending in lines parallel to the lines of the ring shaped bridge portions and lying respectively in substantially the same planes therewith, the insulating distance between the end of a projection and the leg portion of an adjacent strain mem- 20

25

ber being greater than the insulating distance between the projection and the bridge portion of an adjacent strain member.

7. In a device of the kind described, a strain member, said strain member consisting of leg portions connected by a bridge portion, said bridge embodying a ring, and stress distributing projections extending from one portion in lines which are parallel to the lines of the other portion. 30

8. In a device of the kind described, a strain member, said strain member consisting of leg portions connected by a bridge, said bridge embodying a ring, and curved projections extending from a leg portion, the 35 lines of said projections being parallel to the circular line of the ring.

In witness whereof, I have hereunto set my hand at the borough of Manhattan, city and State of New York, this 22d day of April, 1918, 40 45

LOUIS STEINBERGER.

In presence of:—

ISABEL R. RICHARDS,
ZITA M. GRAHAM.
